(57) **CLAIM**

The ornamental design for a fundus imaging apparatus, as shown and described.

DESCRIPTION

FIG. 1 is a front perspective view of a fundus imaging apparatus;

FIG. 2 is a front view of the fundus imaging apparatus;

FIG. 3 is a rear view of the fundus imaging apparatus;

FIG. 4 is a right side view of the fundus imaging apparatus;

FIG. 5 is a left side view of the fundus imaging apparatus;

FIG. 6 is a top view of the fundus imaging apparatus; and,

FIG. 7 is a bottom view of the fundus imaging apparatus.

The broken lines illustrate portions of the fundus imaging apparatus that form no part of the claimed design.

1 Claim, 7 Drawing Sheets
